INVENTOR

UNITED STATES PATENT OFFICE

CHARLEY WASHINGTON, OF BARBOURSVILLE, WEST VIRGINIA.

HARROW.

No. 895,217.

Specification of Letters Patent.

Patented Aug. 4, 1908.

Application filed April 21, 1908. Serial No. 428,311.

To all whom it may concern:

Be it known that I, CHARLEY WASHINGTON, a citizen of the United States, residing at Barboursville, in the county of Cabell and State of West Virginia, have invented certain new and useful Improvements in Harrows; and I do hereby declare the following to be a full, clear, and exact description of the invention, such as will enable others skilled in the art to which it appertains to make and use the same.

This invention relates to new and useful improvements in harrows and has relation more particularly to that class known as folding harrows.

It is an object of the invention to provide a novel device of this character, which when being transported or stored away, can be folded in a small compass.

It is also an object of the invention to provide a novel device of this character, which when in operative position will be thoroughly braced, in order that it may meet all the requirements of practice.

It is also an object of the invention to provide a novel device of this character, wherein means are employed acting in conjunction with a handle thereof for holding the foldable sections of the harrow in operative position.

It is also an object of the invention to provide a novel device of this character which will be simple in construction, efficient in practice and comparatively inexpensive to manufacture.

With the above and other objects in view, the invention consists in the details of construction and in the novel arrangement and combination of parts to be hereinafter referred to.

In describing the invention in detail, reference will be had to the accompanying drawings forming part of this specification, wherein like characters of reference denote corresponding parts in the several views, and in which,

Figure 1 is a view in top plan of the invention. Fig. 2 is a sectional view taken on line 2--2, Fig. 1.

In the drawings, 1 denotes a beam, which may be of any desired length. Passing transversely through the front end portion of the beam, is a bolt 2, which is pivotally engaged by a clevis 3, which swings vertically with relation to the beam when in applied

position. To this clevis is secured any suitable draft rigging. By having this clevis positioned as disclosed, the possibility of undue or unnecessary strain on the draft animals is reduced to a minimum, said strain being caused by any undue vertical movement of the beam.

Intermediate the length of the beam 1 and secured to the sides thereof, through the medium of the hinges 4, are the tooth beams 5, which are adapted to be swung forwardly on the hinges and lie nearly parallel with the beam 1 in close proximity thereto. This permits the harrow to be folded within a small compass, as is believed to be apparent.

The ends of the tooth beams 5 are beveled, so that their movement in one direction will be so limited as to position the beams 5 on a rearward incline when in an operative position. In order that the strain on the hinges 4 may be relieved, blocks 6 are secured to the beam 1 and these blocks are engaged by the beams 5, when in their operative position, as is fully shown in the drawings. The blocks 6, herein referred to are employed in conjunction with the forward beams 5. The blocks 7 acting in conjunction with the rearward beams 5, are of such configuration as to extend beneath a portion of the ends of the beams 5 and said ends of the beams 5 are so formed as to permit such an arrangement.

Extending transversely through the beam 1 adjacent its ends, is a bolt 8, which has secured thereto, on opposite sides of the beam 1, the ends of a handle 9. This handle 9 is formed preferably of a metallic bar, bent as at 10, to form a hand grasp and having the stems 11 terminating in eyes 12, to embrace the bolt 8. The stems 11 intermediate their length are coiled to form eyes 13. Each of the eyes 13 has passing therethrough, the retaining eye 14 of a hook-member 15, which is adapted to engage a staple 16, or other securing means adjacent the rear end portion of the rear tooth beams 5. The staples 16 are embraced by eyes 17 of hook members 18, which engage staples 19, or other fastening means positioned adjacent the rear end portions of the forward tooth beams 5, said staples 16 and 19 being arranged in a plane preferably parallel with the beam 1.

From the foregoing, it will be apparent that the tooth beams 5 are held in operative position by the handle 9.

When it is desired to fold the harrow, it is only necessary to release the hook members 15 and 18 from their fastening means, as is believed to be apparent.

- 5 In order to relieve the stems 11 of the handle 9 from undue strain or pressure, a reinforcing bar 20 is secured thereto, as is fully shown in the drawings. This reinforcing bar may be as desired, but it has been found best
- 10 to have it terminate at both ends in eyes 21, which embrace the stems 11. It is also to be understood that the stems 11 are suitably bent, or of such an angle as to bring the hand grasp 10 in proper position. In order that
- 15 the movement of the stems 11 in a downward direction may be limited, pins 22 project from opposite sides of the beam 1 and on these pins 22, rest the stems 11.

I claim:

In a harrow, the combination of a beam, 20 tooth beams pivoted thereto, a handle pivoted to the beam adjacent one end thereof, means for limiting the movement of the handle on its pivot in one direction, connections between the tooth beams and connections 25 between certain of the tooth beams and the handle.

In testimony whereof I have signed my name to this specification in the presence of two subscribing witnesses.

CHARLEY ^{his} X WASHINGTON.
